UNITED STATES PATENT OFFICE.

WILLIAM T. HICKS, OF BLOOMINGTON, INDIANA.

WIRE-SUPPORT FOR POSTS.

1,045,027.

Specification of Letters Patent.

Patented Nov. 19, 1912.

Application filed December 7, 1911. Serial No. 664,466.

To all whom it may concern:

Be it known that I, WILLIAM T. HICKS, a citizen of the United States, residing at Bloomington, in the county of Monroe and State of Indiana, have invented certain new and useful Improvements in Wire-Supports for Posts, of which the following is a specification.

My said invention consists in an improved form of wire support for fence posts, being designed especially for use with concrete, metallic, or other posts of similar character to which the support can best be attached by a tie, or band, and it consists, further, of a construction which enables such a support to be adjusted to any position desired on said post, or changed from one position to another, all as will be hereinafter more fully described and claimed.

Referring to the accompanying drawings, which are made a part hereof and on which similar reference characters indicate similar parts, Figure 1 is a side elevation of a metallic and concrete fence post having a number of my improved wire supports thereon, Fig. 2, a perspective view of a wire support of my improved construction showing a section of wire therein, Fig. 3, a cross section through the same as attached to a post, and Fig. 4, a detail view of a portion of said support.

The support proper comprises a plate 10, a tie 11, and a securing pin 12. The plate 10 is preferably of galvanized iron, or steel, and is stamped of the form shown with a corrugation *c* midway its length extending across said plate and in line with the post. It has U-shaped slits cut near each end extending parallel with the ends of the plate from near one side to near the other side thereof and back into the plate parallel with its edges for a distance, forming flexible tongues *b* which may be bent out to provide openings through which the ends of the tie 11 may be inserted and then bent back with their ends impinging against the tie and serving to hold it connected to the plate. Said tie 11 consists preferably of a flat piece, or ribbon, of steel, or galvanized iron, of sufficient length to attach to the ends of the plate 10 and surround the post. It being formed wide and flat it will lie snugly against the post and aid in preventing the plate from twisting and moving thereon, and being of a single piece is quickly and conveniently attached.

In use the fence wires 15 are each placed in a transverse notch *a* in the corrugation *c* of the plate and by means of a punch, or similar tool, the portion of the wire registering with said corrugation is crimped back, as shown, and the securing pin 12 inserted in said corrugation passing in front of the wire and through the said crimp therein. The fence wire is thus securely supported longitudinally in said plate, as will be readily understood.

The plate 10 is attached to the post by inserting the tie 11 in the end slits of said plate and then adjusting the support vertically, as desired, and then drawing the tie tightly at the point on the post which it is desired the support shall occupy. The tongues 14 are bent down tightly against the tie and its ends doubled back as shown in Fig. 1. The tie, or band, may be otherwise adjusted, or when the exact size desired has been determined it may be fixed in the plate at both ends and then slid down over the top of the post. The post shown has a flat side against which said plates are designed to rest, thus holding said supports from sliding around the post under the strain from the fence wires. In places where the strain is in a direction to cause the support to slide upward on the post a small quantity of cement, as indicated at *x* in Fig. 1, may be deposited above the top edge of plate 10, which will hold the device securely and guard against any upward movement.

By this means the support is rendered adjustable vertically on the post to any position desired and each fence wire is secured so that each post will carry its proportion of the weight and strain thereof, and a support otherwise convenient of use and inexpensive in construction provided.

Having thus fully described my said invention, what I claim as new and desire to secure by Letters Patent, is:

1. A wire support for posts comprising a plate formed with a corrugation extending across the plate in line with the post and having a notch extending across said corrugation, an opening being formed near the end of said plate by cutting slits therein to form a tongue which is bent outward to form said opening, a tie engaging with said opening and secured therein by bending said tongue down to impinge thereon, a wire formed with a crimp mounted in the notch in said corrugation, and a pin extending

through said corrugation and in front of the wire in line with said crimp, substantially set forth.

2. A wire support for posts comprising a metal plate formed with slits near each end forming flexible tongues in piece with said plate adapted to be bent outward to form openings or to be closed into said slits, a ribbon tie for surrounding the post with its ends engaged in said slits and secured therein by said tongues being bent down to impinge against said tie, said plate being also formed with a corrugation with a notch cutting into said corrugation, a fence wire mounted in

said notch and formed with a crimp at the point of engagement, and a pin adapted to be inserted through said corrugation and in front of the crimp in said wire, substantially set forth.

In witness whereof, I have hereunto set my hand and seal at Indianapolis, Indiana this 29th day of November, A. D. nineteen hundred and eleven.

WILLIAM T. HICKS. [L. s.]
